UNITED STATES PATENT OFFICE.

JOHN HOFFMAN SMITH, OF WASHINGTON, DISTRICT OF COLUMBIA.

DESIGN FOR A COOKING UTENSIL.

SPECIFICATION forming part of Design No. 31,043, dated June 20, 1899.

Application filed May 17, 1899. Serial No. 717,217. Term of patent 14 years.

To all whom it may concern:

Be it known that I, JOHN HOFFMAN SMITH, a citizen of the United States, residing at Washington, in the District of Columbia, 5 have invented and produced a new and original Design for a Cooking Utensil, of which the following is a specification, reference being had to the accompanying drawing, forming part thereof.

10 The drawing represents a perspective of a cooking utensil showing my design and intended to hold food—such as meats, fowl, fish, or vegetables—to be cooked without the use of water, utilizing the liquid contained in the 15 articles to cook them in a covered kettle, pot, or skillet.

As shown in the drawing, the leading or

material feature of my design consists of a flat reticulated body A, having a surrounding rim B, feet or supports C, and a guard D 20 above the plane of the body A and joined thereto by bars a.

Having described my invention, what I claim as new, and desire to secure by Letters Patent, is—

25 The design for a cooking utensil, substantially as herein shown and described.

In testimony whereof I affix my signature in presence of two witnesses.

JOHN HOFFMAN SMITH.

Witnesses:

D. C. REINOHL,
W. PARKER REINOHL.
